EDUCATIONAL DEVICE

Allan H. Teeter, 1391 Edgewood Road,
Redwood City, Calif.

Filed Aug. 1, 1960, Ser. No. 61,576

Term of patent 3½ years

(Cl. D25—1)

FIG. 1.

FIG. 2.

FIG. 3.

FIG. 4.

FIG. 1 is a front elevational view of of an Educational Device, showing my new design;

FIG. 2 is a side view of the same.

FIG. 3 is a back view, in perspective, of the device.

FIG. 4 is a vertical cross section taken substantially in the center of my device.

The essential features of my educational device reside in the rear portion comprising a U-shaped support that tapers outwardly from top to bottom forming a cavity within, said cavity having at its base a sloping shelf upon which resides a keyboard comprised of two parallel rows of buttons, and at its upper portion a semi-circular box with marginal grooves thereon, all as shown.

I claim:

The ornamental design for an educational device, substantially as shown and described.
